CLAIM

Sep. 15, 2003 (FR) 03 10817

The ornamental design for a packaging device for a windscreen wiper, as shown and described.

(51) **LOC (9) Cl.** **09-03**

DESCRIPTION

(52) **U.S. Cl.** **D9/415; D9/425**

The sole FIGURE is a bottom, front, and right side perspective view of a packaging device for a windscreens wiper, showing our design.

(58) **Field of Classification Search** D9/722, D9/414-416, 418, 419, 424-426, 457; 206/459.5, 206/461-471, 486, 495, 335, 349, 361, 448, 206/1.5, 776, 778, 806, 822

The flange, ledge, and recess surfaces of the packaging device for a windscreens wiper shown in the sole FIGURE are only curved around the Z-axis such that the flange, ledge, and recess surfaces are curved in the X-Y plane. When viewed from a front elevational view, the Z-axis is perpendicular to the flange, ledge, and recess surfaces. Thus, the flange, ledge, and recess surfaces of the packaging device for a windscreens wiper shown in the sole FIGURE are not curved in the Z-X and Z-Y planes.
